UNITED STATES PATENT OFFICE.

ADRIAN ETHELBERT CARTER, OF MANCHESTER, ENGLAND, ASSIGNOR TO HANS RENOLD LIMITED, OF DIDSBURY, MANCHESTER, ENGLAND, A CORPORATION OF GREAT BRITAIN AND IRELAND.

APPLIANCE FOR EXTRACTING OR INSERTING STUDS OF DRIVING-CHAINS.

1,208,092.

Specification of Letters Patent.

Patented Dec. 12, 1916.

Application filed November 3, 1914. Serial No. 870,109.

To all whom it may concern:

Be it known that I, ADRIAN ETHELBERT CARTER, a subject of the King of Great Britain, and resident of Progress Works, 5 Brook street, Manchester, England, have invented certain new and useful Improvements in Appliances for Extracting or Inserting Studs of Driving-Chains, of which the following is a specification.

10 This invention relates to appliances for extracting studs from, or inserting them into the link-plates of driving chains—for instance when a damaged link is to be replaced by a new one. The device is of the 15 type wherein the link-plates are supported by the jaw of a cramp while the stud is being forced out of or into position by a screw-stem or the like.

It is the principal object of the invention 20 to provide appliances for extracting or inserting studs of driving chains, which shall be applicable to chains such as are used on motor cycles and pedal cycles, and shall operate without tightening the link-plates 25 against the roller and thus preventing it from turning on the bush.

A further object is to provide a tool which can be used with various sizes of chains.

30 The invention is illustrated in the accompanying drawings, in which:—

Figure 1 is a perspective view of a screw-cramp; Fig. 2 is an end elevation of the screw-cramp in a position for extracting a 35 stud; Fig. 3 is a side elevation of the screw-cramp with the fork hinged back and a chain link in the position for inserting a stud, and Fig. 4 is a perspective view of a screw-cramp with four movable forks.

40 Referring more particularly to Figs. 1, 2 and 3, *c* is the frame of a screw-cramp having a slotted jaw at *a*, and *b* is a fork pivoted to the said frame by means of a screw pin *j*. In the type of cramp illustrated, a screw-stem *d* works in a boss *e* formed on the frame *c*. In Figs. 2 and 3 a piece of bush roller chain is shown in the cramp, in the positions for extracting and for inserting a stud respectively.

50 When studs are to be inserted they will be already carried at one end by the outer link-plate *g* of Fig. 3. The other outer link-plate *h* is placed as in Fig. 3 to straddle the slot *n* of the jaw *a*, and the end of one stud *f*

is then forced into the stud-hole by the 55 thrust pin *d*, which is screwed down onto the stud *f* as in Fig. 3. The stud at the other end of the link plate *g* is then forced into the link plate *h* in the same manner.

When a stud is to be extracted the upper 60 link-plate *g*, Fig. 2, is supported by the prongs of the fork *b* which are adapted to pass under and support the upper link-plate of the inner combination on each side of the roller, as shown in Fig. 2. The upper 65 end of the stud can then be forced out of the upper link-plate *g* of the outer combination by means of the thrust pin *d*.

Stud-cramps made in accordance with the present invention may be constructed to 70 operate on a wider range of different sizes of chain by providing them with several forks one for each range of sizes. Then each fork can be used also as a jaw for the insertion of studs. Such a stud-cramp, with 75 four forks, is shown in perspective in Fig. 4, although only three of the forks are visible. These forks *b*⁴, *b*⁵, *b*⁶ are formed on or attached to a boss *k*, which is adapted to slide to and fro, and also to turn upon, a 80 cylindrical stub *l*, which is carried at the lower end of the frame *c* by means of a boss *m*. This boss is provided with a ledge *o'* to serve as a support for the free ends of the forks. The slots of the forks may be 85 formed of gradually varying width, as shown in the fork *b*⁵, or they may be cut to one width part of the way, and of a narrower width for the rest of the way, as shown in the fork *b*⁴. When a stud is to 90 be extracted the boss *k* is pulled back along the stub *l* until the free ends of the forks are clear of the support *o'*. A stop or enlarged end *p* prevents the boss *k* from coming off the stub *l*. The chain-joint is then supported 95 on the outer or end part of a fork of appropriate size, in the manner shown in Fig. 2; the boss is turned if necessary, so that when it is pushed forward again the free ends of the selected fork will be supported 100 by the ledge *o'*. The fork is then pushed forward until the stud is underneath the thrust pin *d*, by which it can be forced out as already described. When a stud is to be inserted, the lower link-plate is laid on 105 the top of the fork but nearer to its base, the fork then acting as the jaw *a* of Figs. 1 to 3; the chain-joint with the link-plate

- already carrying the studs in place is held in position above it, so that the stud can be forced home by the thrust pin *d*. In the figure the fork in use is shown in the position which it would occupy when a stud is to be inserted; when a stud is to be extracted the fork would be drawn back a little along the stub *l*, to bring the center of the wider part of the slot underneath the thrust pin *d*.
- 10 It will be obvious that when there is a set of forks *b** as in Fig. 4, a fork which is used for extracting studs from chains of one size, will serve also for the insertion of studs in chains of the next larger size.
- 15 Having thus described my invention what I claim as new and desire to secure by Letters Patent is:—
1. A chain cramp for use in extracting and inserting the studs of driving chains, comprising a thrust-pin, a fork adapted to pass between the links of a chain, a frame carrying the thrust-pin, means for movably supporting the fork on the frame and permitting it to be adjusted in position relatively to the thrust-pin, and means for operating the thrust-pin.
2. A chain cramp for use in extracting and inserting the studs of driving chains, comprising a thrust-pin, a frame carrying the same and means for operating the thrust-pin, a fork and means for carrying the same in a movable manner on the frame, said fork having jaws wider at one part than another, and adapted to pass between the links of a chain and to support the inner upper link-plate while the stud is being forced out of the outer upper link-plate.
3. A chain cramp for use in extracting and inserting the studs of driving chains, comprising a thrust-pin, a frame carrying the same, means for operating the thrust-pin, a stub on the frame, a boss adapted to slide thereon, a fork on said boss, said fork being wider at its outer part than at its rear part, the outer part being adapted to pass between the links of a chain when a stud is to

to be removed, and the rear part of the fork being adapted to support the outer link plate of a chain when a stud is to be forced thereinto, while the movements of the boss on the stub enable either part of the fork to be brought into line with the thrust pin.

4. A chain cramp for use in extracting and inserting the studs of driving chains, comprising a frame, a thrust pin carried thereon, means for operating the thrust pin, a stub, a boss adapted to slide and to turn thereon, and a plurality of forks on said boss, said forks being of different widths one from another, whereby one or other fork can be brought into position in line with the thrust pin according to the dimensions of the chain to be operated upon.

5. A chain cramp for use in extracting and inserting the studs of driving chains, comprising a thrust pin, a frame carrying the same, means for operating the thrust pin, a stub on the frame, a boss adapted to slide thereon, a fork on said boss, said fork being wider at its outer part than at its rear part, the outer part being adapted to pass between the links of a chain when a stud is to be removed, and the rear part of the fork being adapted to support the outer link plate of a chain when a stud is to be forced thereinto, a ledge on the frame over which the end of a fork can slide when in line with the thrust pin, said ledge being adapted to assist in bearing the thrust on the fork during the extraction and removal of studs from a chain, while the sliding movement is sufficient to withdraw the fork from the ledge in order to permit of the insertion of the fork between the links of a chain.

In witness whereof, I have hereunto signed my name this 25th day of September, 1914, in the presence of two subscribing witnesses.

ADRIAN ETHELBERT CARTER.
